[57] CLAIM

The ornamental design for a cylindrical lampholder in

FIG. 1 is a perspective view of the cylindrical lampholder in U-shaped wire holder for use on track showing our design;

FIG. 2 is a front elevational view of the cylindrical lampholder in U-shaped wire holder for use on track shown in FIG. 1;

FIG. 3 is a left side elevational view of the cylindrical lampholder in U-shaped wire holder for use on track shown in FIG. 1;

FIG. 4 is a right side elevational view of the cylindrical lampholder in U-shaped wire holder for use on track shown in FIG. 1;

FIG. 5 is a rear elevational view of the cylindrical lampholder in U-shaped wire holder for use on track shown in FIG. 1;

FIG. 6 is a top view of the cylindrical lampholder in U-shaped wire holder for use on track shown in FIG. 1; and,

FIG. 7 is a bottom view of the cylindrical lampholder in U-shaped wire holder for use on track shown in FIG. 1. The broken lines are shown for illustrative purposes only and form no part of the claimed design.

FIG. I

FIG. 2
